UNITED STATES PATENT OFFICE.

HENRY HERBERT YELF, OF SOUTHSEA, ENGLAND.

LOCKING DEVICE FOR TYPE-WRITING MACHINES.

1,037,399.

Specification of Letters Patent.

Patented Sept. 3, 1912.

Application filed September 22, 1911. Serial No. 650,760.

To all whom it may concern:

Be it known that I, HENRY HERBERT YELF, a subject of the King of Great Britain, residing at Southsea, in the county of Hampshire, England, have invented a new and useful Improvement in Locking Devices for Type-Writing Machines, of which the following is a specification.

This invention relates to improvements in and relating to accessory devices for type-writing machines and has for its object to provide a device adapted to be locked in the typewriting machine and in its locked position to prevent the type bars from being operated, so that only persons in possession of a key capable of unlocking the device, are able to have access to the machine for writing purposes.

In the specification accompanying my previous application of the United States of America Serial Number 572585 filed July 18th 1910 there is described a pan or receptacle adapted to be inserted into the typewriting machine so as to partly lie under the platen and to receive the debris arising from erasing operations performed against the platen. For front-strike typewriters the receptacle was conveniently given the shape of the cavity in a front-strike typewriting machine, which cavity as is well known is curved or part cylindrical. Now if such a receptacle be locked in the cavity aforesaid it is clear that the type bars will not be able to rise in order to strike an impression upon the paper on the platen.

In particular, therefore, the present improvements may be said to consist in providing the receptacle aforesaid with a lock for securing it in the typewriting machine, but there is a larger scope comprised by the present improvements, inasmuch as the part-cylindrical or other shaped object which, according to these improvements, is fitted with a lock for enabling the object to be locked to the framing of the machine in the before mentioned relation to the type bars, may take the form of a debris receptacle as aforesaid, or of a container for eraser, pencil and tools and so on, such container having say, a lid or cover provided with a suitable lock or fastening, or of an oil container or can, or the device might have no receptive capacity but might be a mere dummy adapted to bear advertising matter and adapted for locking the machine and for nothing else.

In order to enable this invention to be

readily understood reference is made to the accompanying drawings in which—

Figure 1 is a central vertical section from front to rear of one example of the improved locking device as applied to a typewriting machine only sufficient parts of the latter being shown to enable the application of the device to be appreciated. Fig. 2 is a transverse section of the locking device removed and as seen when looking toward the rear, the lock being in the operative position. Fig. 3 is a similar view but showing the lock in the inoperative position. Fig. 4 is a view similar to Fig. 1 but showing the lock in the inoperative position. Fig. 5 is a plan of a suitable key for use with this device. Fig. 6 is a view similar to Fig. 1 showing a modified form of locking device as applied to a different construction of typewriting machine. Fig. 7 is a side elevation of the key removed. Fig. 8 is a front elevation of the locking device removed. Fig. 9 is a view similar to Fig. 6 but showing the lock in the inoperative position. Fig. 10 is partly a rear elevation and partly a transverse section of a further modified form of locking device, and Fig. 11 is a plan and Fig. 12 a central vertical section from front to rear of the same.

According to the examples illustrated by the drawings the device is adapted to be used as a dust and debris receptacle.

In Figs. 1 to 4 the receptacle *a* has an open end *b*, or an end flange which takes beneath a curved or other part *c* of the framing beneath the platen *d*, when the receptacle is placed upon or over the type bars *e* and is moved into its receptive position in which it is seen in Figs. 1 and 4. According to this arrangement a rod *f* is revolvably mounted in lugs or brackets *g* fixed on the underside of the receptacle *a* and one end may be formed or fitted with a catch *h* or device adapted, when the rod *f* is turned, to engage behind the said framing member *c*. At its opposite end the rod *f* carries a cam *j* or the like and a spring *k*, which may encircle the rod *f*, acts upon the latter so as to always tend to maintain the cam *j* in the path of a key *l* and the catch *h* in the operative position as seen in Fig. 1. A block *m* or key guide formed with a suitable key slot or aperture *n* is fitted in such a position that when the correspondingly shaped key *l* is inserted in the key-way *n* as shown in Fig. 4, the cam *j* is pushed around

in one direction against the action of the spring *k* and the catch *h* is turned to inoperative position. As shown in Fig. 5, the edge *o* of the key has a suitable stepped or cam formation in order to enable the cam to be moved aside by merely forcing the key *l* into the key-way *n*. When the key *l* is withdrawn, the catch *h* is moved by the spring *k* to the operative position seen in Fig. 1. The whole of the parts of the lock 10 may be inclosed in a suitable housing *p* fixed on the underside of the receptacle *a*. Therefore it will now be understood that if the receptacle *a* or other object having the key *l* inserted, be placed in position over the type bars *e* in the typewriting machine and the key *l* be then removed, the spring *k* will throw up the catch *h* behind the adjacent framing member *c* and only a person 20 possessing a properly shaped key will be able to release the catch *h* and remove the receptacle or object *a* to enable the machine to be used for writing. As seen in these figures the receptacle *a* is fitted with a rubber shoe or guard *q* on the edge of an extension *r* of the front wall, which extension reaches below the body of the receptacle *a*. The front wall which rests upon the type 30 bars *e* is thus prevented from scratching or injuring the enamel or the like on the type bars *e*. The interior of the receptacle is fitted with an upstanding flange *s* which fits against the front surface of the framing member *c* and prevents the receptacle from being inserted too far into the machine. 35

In another example illustrated by Figs. 6 to 9, a bar, rod or arm *t* having a catch *u* which may be downwardly directed is so disposed that the catch *u* is adapted for engaging behind the inking pad support *v* of a certain make of machine. The rod or arm *c* is pivotally mounted in a bracket *w* fixed in a suitable housing *w*, which may actually be within the receptacle *a* or other object so 45 that the latter possesses no exterior projection as is the case when the housing is exteriorly arranged as in Figs. 1 to 5. A blade or other spring *y* may be arranged to constantly tend to depress the arm *t* to 50 move its catch *u* into operative position so that in this arrangement, as in the foregoing, the key *l* must be in position when the receptacle or object *a* is put into the machine and then upon withdrawing the 55 key *l* the spring *y* will depress the arm and catch into the position seen in Fig. 6 and the device will be locked in position in the typewriting machine and will prevent the type bars from being thrown upward as 60 will now be well understood. The key *l* in this arrangement may be of inverted T-section as shown and be formed with a suitably inclined end *z* for lifting the arm *t*. 65

The construction shown in Figs. 10 to 12 is very similar to that shown in Figs. 6 to 9, but in this arrangement the arm or bar *t* is bifurcated at 1 and the inturned ends 2 are inserted through holes in a sheet metal bracket 3 to form a pivotal connection. A bow spring 4 is preferably connected at one end to the arm *t* while the other end takes beneath the bracket 3 the spring 4 constantly tending to depress the arm *t* and catch *u*. Between the bifurcated parts 1 there is a downwardly bent portion 5 on the bar which reaches into the path of the key *l*. The inner end of the key *l*, when nearly pressed home, comes over a bent spring blade 6 which as the key is pressed home raises the inner end of the key thereby completely raising the arm *t* and catch *u*. In any of the constructions shown, and as seen in Figs. 1, 4, 10, 11 and 12, the receptacle *a* may be fitted interiorly with clips 7 for supporting erasers or other appliances or instruments used in connection with typewriting. In the constructions shown in Figs. 6 to 12 the receptacles are formed or fitted with wide side flanges 8 which may assist in supporting the receptacle by taking over and resting upon the upper surface of the frame of the machine. 70 75 80 85 90 95 100 105 110 115 120 125 130

It is obvious that, while locks of the kind described are advantageous, the invention is not particularly concerned with special constructions of lock as these may be of widely differing types. The essence of the invention is the provision of an object which is capable of being locked in relation to the type bars of a typewriting machine so that the latter is inoperative when the object is in position and can only be used by persons possessing a key enabling them to release and remove the object as aforesaid, said object being preferably in the form of a receptacle that will serve as a debris collector as well as a tool holder. 100

What I claim is:—

1. A locking device for a typewriting machine comprising an object applicable to said machine in such a position as to render the type bars thereof inoperative, a lock on said object adapted to be engaged with a suitable part of such machine and to fasten said object in said position, and a cushioning shoe carried by the object for engaging the type bars. 110
2. A locking device for a typewriting machine comprising an object adapted to be inserted into a cavity or space in said machine within range of the type bars, a housing carried by the object, and a lock in said housing adapted to be engaged with a suitable part of said machine and to fasten said object in said cavity. 120
3. A locking device for a typewriting machine comprising an object conforming somewhat with and insertible into a space or cavity in said machine, said space being bounded on one side by the type bars, a base 130

housing carried by the object, and a lock in said housing adapted to be engaged with a suitable part of said machine and to fasten said object in said space or cavity.

5. 4. A locking device for a typewriting machine comprising a receptacle insertible into a space or cavity in said machine, supporting flanges on said receptacle adapted to engage said machine, and a lock on said receptacle adapted to be engaged with a suitable part of said machine and to fasten said receptacle in said space or cavity.

10. 5. A locking device for a typewriting machine comprising an object applicable to said machine in such a position as to render the type bars thereof inoperative, a housing carried by the object, a lock in said housing adapted to be engaged with a suitable part of such machine and to fasten said object in said position, means in said housing constantly tending to render said lock operative, and a key adapted when inserted to hold said lock inoperative.

15. 6. A locking device for a typewriting machine comprising an object applicable to said machine in such a position as to render the type bars thereof inoperative, a catch on said object adapted to engage a part of said machine and to retain said object in said position, a spring constantly tending to force said catch into operative position and a key adapted to engage said catch and to hold the latter in the inoperative position.

20. 7. A locking device for a typewriting machine comprising an object insertible into a cavity bounded on one side by the type bars,

supporting means thereon adapted to engage said bars, locking means on said object adapted to be engaged with a suitable part of the machine to retain said object in said cavity, and tool holding means carried by the object.

25. 8. A locking device for a typewriting machine comprising an object insertible into a cavity in said machine bounded on one side by the type bars, locking mechanism on said object comprising a movable catch adapted to be engaged with a suitable part of said machine, means constantly tending to move said catch to operative position, and a sliding key adapted when inserted into the lock to operate said mechanism for moving said catch to inoperative position substantially as set forth.

30. 9. A locking device for a typewriting machine comprising a hollow receptacle shaped to fit within the space bounded on one side by the type bars of said machine, a housing on said receptacle, locking mechanism within the housing, a catch under the influence of said mechanism and adapted to be engaged thereby with a suitable part of said machine, and a key insertible through a key hole and adapted to enter said housing in order to operate said mechanism for the removal of said catch from operative position and for holding said catch inoperative substantially as set forth.
